KEY RING AND HOLDER THEREFOR

Stephen Peters, Omaha, Nebr.

Application April 16, 1937, Serial No. 137,237

5 Claims. (Cl. 70—456)

This invention relates to an improvement in key rings, and includes a holder for supporting a key ring. The invention has for its objects to provide such a construction that a key will not become detached from the ring accidentally but will require intentional, manual force for said detachment, but will be convenient in use to permit keys to be placed on the ring. The invention includes a holder of such construction that the key ring will not become detached therefrom except by intentional manual force of an operator, but will permit convenient and ready attachment of the key ring.

The invention consists of the new and useful construction, combination and arrangement of parts as described herein and claimed, and as illustrated in the accompanying drawing, it being understood that changes may be made in form, size, proportions and minor details, said changes being within the scope of the invention as claimed.

In the drawing, Fig. 1 is a view in front elevation of a key ring and holder therefor embodying my invention, a part of a belt being shown.

25 Fig. 2 is a side view of the device.

Fig. 3 is a front view of the key ring and its locking-band and Fig. 4 is a side view of the same. Fig. 5 is a view similar to the view shown in Fig. 3, the locking-band being omitted.

30 Fig. 6 is a front view of the ring holder. Fig. 7 is a side view of the same. Fig. 8 is a top plan view of the locking-ring and Fig. 9 is a top plan view of the key ring.

Referring now to the drawing for a more particular description, the key ring-portion 10 is provided with a pair of approximately parallel arms 11 and 12, each provided with a notch 13 best shown in Fig. 5 of the drawing, the arm being provided near its end with a pair of opposed notches or slots 14 (Fig. 4).

The arm 12 has a part which is disposed at right-angles thereto to provide a locking-bar 15 having a slot 16 opening on its end as best shown in Fig. 9; and on account of the formation of the slot 16 a pair of contact-fingers 15' will be provided.

Numeral 17 indicates an elongated locking-band adapted to engage in the notches 13 for enclosing the arms 11 and preventing said arms from moving outwardly from each other and thereby preventing the loss of keys (not shown) which might be carried by the ring.

Also it will be noted that any outward swing-55 ing movement of the locking-bar 15 will be pre-

vented since the fingers 15' engage in the pair of slots 14 of the arm 11.

The ring-portion 10 is constructed of resilient material, such as spring-steel, and in operation, for mounting a key thereon (the key, as usual, being provided with a loop for receiving the ring 10), the arms 11 and 12 are manually pressed toward each other until the band 17 becomes loose on said arms, and after this band is released from the notches 13 it may be readily removed. The arms 11 and 12 may then be manually pressed outwardly from each other until the fingers 15' move from the slots 14 of the arm 11 to permit the key to be mounted on said ring-portion 10.

After a key has been mounted on the key ring, the arms 11 and 12 are manually pressed toward each other, the slot 16 of the locking-bar 15 being of adequate length to permit said arms to approach each other when forcibly pressed, and the band 17 is then replaced in normal position 10 on said arms and in engaging position with the notches 13.

To remove keys from the key ring the operation, of course, will be reverse to the operation described.

It may be stated that at least two locking means are provided to prevent accidental loss of keys from the ring, one being the arm 15 which is locked in the slots 14, and the band 17 which prevents spreading apart of arms 11 and 12.

Since key rings are often supported upon belts and are subjected to severe stresses and usage especially when loaded with a large number of keys, they should be of strong construction, and in the present instance it will be seen 35 that the locking-band 17 is firmly seated in the notches 13 and is held in normal position since the arms 11 and 12 resist any pressure toward each other.

To permit the key ring to be carried about I 40 provide a holder 18 consisting of a single metallic strip, bent to form a loop for receiving a belt 23 or other support, said loop consisting of a pair of approximately parallel members 19 and 20, bent adjacent to their ends to form a hook 21 45 for receiving the locking-bar 15, the loop-member 20 being bent outwardly above the hook 21 to provide a guide or contact-finger 22 for convenience when attaching the key ring to the keyholder.

While the key ring, together with the keys thereon, could be carried in the owner's pocket, it is the custom, generally, to carry the ring on a belt, especially when a considerable number of keys are to be carried, and it will be appreciated 55

that the key ring may be conveniently attached to or detached from the holder, and it will not become detached therefrom accidentally since the form of the hook and finger 22 provide a constricted passageway *x* at the top of the hook.

I claim as my invention,—

1. A key ring comprising a curved resilient body-member provided with a pair of opposed, outwardly projecting arms, one of said arms being provided with a pair of slots, the other arm of said pair having a part bent at approximately right-angles therefrom and providing a locking-bar with terminal contact-fingers for slidable movements in the slots of the first named arm, and a locking-band embracing said arms for preventing a sliding movement of said locking-bar.

2. In a key ring, a resilient body of circular form having a pair of outwardly projecting flexible arms, one of said arms being provided with a pair of slots, the other arm of said pair being bent at right-angles to provide a locking-bar for a slidable movement in the slots of the first named arm, and means on said arms to prevent a slidable movement of the locking-bar relative 25 to said first named arm.

3. In a key ring, a resilient body of circular form provided with a pair of outwardly projecting arms each provided with a notch, one of said arms being provided with a pair of opposed slots, 30 the other arm of said pair having a part disposed at right-angles thereto to provide a locking-bar

with contact-fingers for detachable engagements and a slidable movement in the slots of the first named arm, and a locking-band adapted to be seated in said notches in engagement with said arms.

4. In a key ring, a metallic strip of circular form provided with a pair of outwardly projecting arms, one of said arms having a part disposed at right-angles thereto to provide a locking-bar for engaging the first named arm, said arms being resilient to permit longitudinal movements of the locking-bar for disengagement from said first named arm, and a locking-band extending around said arms to prevent longitudinal movement of the locking-bar.

5. In a key ring, a metallic strip of circular form provided with a pair of outwardly projecting arms provided with notches, one of said arms being provided near its end with a pair of opposed slots, the other arm of said pair having a part bent at right-angles therefrom to provide a locking-bar provided with a pair of contact-fingers for engaging in the slots of the first named arm to prevent lateral movements of said locking-bar, said arms being resilient to permit sliding movements of said contact-fingers in the slots of the first named arm, and a locking-band adapted to be disposed in engagement with said arms in the notches thereof.

STEPHEN PETERS. 30
